UNITED STATES PATENT OFFICE.

WILLIAM S. WILKINSON, OF ELIZABETH, NEW JERSEY, ASSIGNOR TO BETHLEHEM SHIPBUILDING CORPORATION, LTD., A CORPORATION OF DELAWARE.

OIL-BURNING-FURNACE FRONT.

Application filed April 25, 1923. Serial No. 634,574.

To all whom it may concern:

Be it known that I, WILLIAM S. WILKINSON, a citizen of the United States, and a resident of Elizabeth, Union County, and

State of New Jersey, have invented certain new and useful Improvements in Oil-Burning-Furnace Fronts, of which the following is a specification.

The present invention relates to oil burners for the front of oil burning furnaces.

In Patent No. 1,431,763 issued October 10, 1922 to Thomas Service is disclosed an oil burning furnace front, in which either forced or natural draft may be employed and which has a number of novel and important features rendering it of greater value, from a practical point of view, than furnace fronts of this type theretofore designed or constructed. The furnace front 20 which comprises the subject matter of that patent includes a casing adapted to be directly secured to the boiler or furnace front having an air duct or conduit a novel arrangement of vanes between which the air is admitted either under natural draft or under forced draft to the atomized fuel, a novel valve construction for regulating the flow of air through the air conduit provided, whereby the quantity of air fed may be positively and accurately controlled or completely shut off if desired, a novel means for supporting the burner, and other new and advantageous features.

The present invention constitutes an improvement upon the burner disclosed in the patent mentioned and its principal objects are: first, to provide a front for an oil burning furnace which permits the use of either air under pressure from a forced draft air duct, or the utilization of air under atmospheric pressure only and taken directly from the air surrounding the furnace instead of from the air duct, and second, to provide a front having a novel construction whereby the operator is enabled to swing the burner parts outwardly quickly and conveniently, for the purpose of inspection, cleaning and repair. This improved front is particularly useful in cases where it comprises a unit in a battery of burners, all of which are supplied with air under pressure from a common duct or common source of supply. The construction is such that the burner parts of one or more burners of the battery may be in-

spected, cleaned or repaired without cutting off the forced draft air supply to the other burners so that the furnace operation is uninterrupted.

Other objects and advantages of the invention, will be apparent to one skilled in the art and it will be also obvious that changes may be made in the design and arrangement of the component elements without departing from its spirit and scope.

In the drawing:

Figure 1 is a front elevation of the furnace front;

Figure 2 is a vertical axial section through the same;

Figure 3 is a similar view with certain parts of the front illustrated in different positions;

Figure 4 shows the furnace front in perspective; and

Figure 5 is a detail view of a latching device.

The spaced walls of the air duct for forced draft are indicated at 10 and 11 respectively, the outer wall 10 constituting the front of the furnace and the inner wall 11 lying adjacent the refractory furnace lining, which is not illustrated except in that a portion of the furnace ring is indicated at 12 in Figures 2 and 3. Secured between walls 10 and 11, and co-axial with the furnace ring, is the annular air directing device, comprising spaced ring members 13 and vanes 14, which is constructed and arranged to direct tangential streams of air into the burning space, as clearly described in the patent previously referred to. A cylindrical or sleeve-like valve member 15 slidably fits within rings 13 and is adapted to be axially adjusted in the operation of the burner to control the quantity of air flowing from the forced draft duct.

An annular frame indicated at 16 is hinged at 17 to swing about a vertical axis and is provided with a flange 18 diametrically opposite the hinge, which flange is notched at 19 to receive a lug or boss 20 extending outwardly from the outer ring 13. A latch pin 21 rests in a vertically extending aperture in the lug 20 and normally holds the swinging frame 16 in the position illustrated in the drawings, with its inner edge in contact with the outer ring 13 of the vane supporting member. Extending outwardly from the swinging frame and com-

prising a portion thereof, are arms 22 to the outer ends of which is bolted the cross-piece 23. This cross-piece has formed integrally therewith a tubular member 24 extending axially of the furnace ring and which slidably supports a substantially disk-shaped member 25. The edge of this disk member is adapted to seat against an annular shoulder 26 formed on the inner wall of 10 cylindrical valve member 15.

Disk 25 may be locked to the cylindrical member 15 by means of latches 30 secured on the inner ends of spindles 31 rotatably supported in bearings in disk 25. To the 15 outer ends of these spindles are secured operating handles 32 for rotating the same. The latches 30 are designed to engage catches 33 formed as webs or flanges springing from the inner wall of member 15, the 20 mutually engaging faces of latches 30 and catches 33 being inclined to planes at right angles to the axes of rods 31. The catches therefore are in the nature of cams by means of which the disk member 25 may be drawn 25 against the seating shoulder 26 with any desired degree of tightness. Lighting torch holes 36 are formed in the disk valve member 25, these holes being normally closed by doors 37 provided with sight openings 38 30 through which the flame may be watched. These sight openings are normally closed by swinging plates 39.

The tubular member 24 slidably receives a cylinder 40 to the inner end of which is 35 secured the slotted cone 41. The oil supply tube is indicated at 42 and it extends through tube 40, its inner end being held axially therein by a spider 43. An oil atomizing device 44 is secured to the inner end 40 of the oil tube. To the outer end of the oil supply tube is connected the structure S which includes the control valve, straining devices, and other features which will not be herein described in detail. The structure 45 S is supported by a bracket secured to the member 24.

When operating under forced draft, the disk 25 is seated on shoulder 26, as shown in Figure 2, and the disk and cylindrical sleeve valve 15 are adjusted axially of the burner as one unit in the manner fully described in the patent to Thomas Service before referred to, to admit more or less air to the burning space. If however it is desired to operate under natural draft, the latches 30 are manipulated so that the disk and cylinder of the valve structure may be separated as shown in Figure 3, the cylindrical portion 15 of the valve structure remaining in its innermost position and closing the annular outlet of the forced draft air duct, while the disk 25 is moved outwardly on the supporting tube 24 to the position shown in Figure 3 so that atmospheric air may freely flow into the furnace. To further increase

the effective opening, the doors 37 may be swung aside if desired.

While any desired means may be employed for axially adjusting the valve members, I prefer to employ a pinion and gear construction such as disclosed in the drawings. A rod 50 arranged parallel to tube 24 has its inner end rigidly connected to disk 25, and the toothed under portion of this rod constitutes a rack meshing with a pinion 51 on a short shaft 52 controlled by a hand wheel 53. Rotation of the hand wheel effects axial movement of the rod and disk 25 and it will be seen that this means constitutes a common control means for the air supply valves, whereby either the amount of air flowing under forced draft to the burner may be controlled, or the amount of air under natural draft.

With the disc and cylinder of the valve structure separated as shown in Figure 3 (the forced draft having been cut off by means of the cylindrical portion 15), the removal of the pin 21 will permit the swinging of the annular frame 16 about its hinge 17. The burner is then readily accessible for inspection or repair without interference to the forced draft air supply to other burners in the same battery.

Having thus described the invention what is claimed as new and desired to be secured by Letters Patent is:

1. The combination with a furnace port of an oil spray device adjacent to the same, a forced-draft air duct having an annular outlet adjacent to and coaxial with the furnace port, an open-ended tubular valve for controlling the flow of air from said duct to the furnace port, a second valve adapted to seat against the open end of said tubular valve and movable toward and away therefrom for controlling the flow of atmospheric air through said tubular valve to the furnace port, means for securing the valves together, and means for moving the second valve inwardly and outwardly.

2. The combination with a furnace port of an oil spray adjacent the same, a forced draft air duct having an annular outlet adjacent and coaxial with the furnace port, an open ended cylindrical valve controlling the flow of air from said duct to the furnace port, and a disk valve in rear of said cylindrical valve for controlling the flow of atmospheric air through said cylindrical valve to the furnace port, said disk valve being adapted to seat on said cylindrical valve.

3. The combination with a furnace port of an oil spray adjacent the same, a forced draft air duct having an annular outlet adjacent and coaxial with the furnace port, an open ended cylindrical valve controlling the flow of air from said duct to said furnace port, a disk valve in rear of said cylindrical valve for controlling the flow of atmos-

pheric air through said cylindrical valve to the furnace port, and means for locking said disk valve to said cylindrical valve.

4. The combination with a furnace port 5 of an oil spray adjacent the same, a forced draft air duct having an annular outlet adjacent and coaxial with the furnace port, an open ended cylindrical valve controlling the flow of air from said duct to said furnace 10 port, a disk valve in rear of said cylindrical valve for controlling the flow of atmospheric air through said cylindrical valve to the furnace port, and manually operable latch means for locking said disk valve to said 15 cylindrical valve.

5. The combination with a furnace port of an oil spray adjacent the same, a forced draft air duct having an annular outlet adjacent and coaxial with the furnace port, an open ended cylindrical valve controlling the flow of air from said duct to the furnace port, an annular rearwardly facing seating surface on said cylindrical valve, and a disk valve in rear of said cylindrical valve and adapted to seat on the annular seating surface of said cylindrical valve, said disk valve controlling the flow of atmospheric air through said cylindrical valve to the furnace port.

20 6. The combination with a furnace port of a forced-draft air duct having an outlet port adjacent to the furnace port, an air supply control means including a valve for controlling the flow of air from said duct to said furnace port, a second valve for controlling the flow of atmospheric air to said furnace port, a swinging frame for carrying the second valve, and an oil atomizing device mounted on the swinging frame.

25 7. The combination with a furnace port of a forced draft air duct having an outlet port adjacent the furnace port, a valve for controlling said outlet port, a swinging frame, an oil atomizing device mounted on the swinging frame, and a second valve mounted on the swinging frame for controlling the flow of atmospheric air to the furnace port.

30 8. The combination with a furnace port of a forced draft air duct having an annular outlet port adjacent and coaxial with the same, a cylindrical open ended valve controlling said port, an oil atomizing device, a second valve for controlling the flow of atmospheric air through the cylindrical valve, and a movable frame upon which the second valve and atomizing device are mounted.

35 9. The combination with a furnace port of a forced draft air duct having an annular outlet port adjacent and coaxial with the same, a cylindrical open ended valve con-

trolling said port, a hingedly mounted frame, an oil atomizing device mounted on this frame, a second valve adjustably mounted on the frame for controlling the flow of atmospheric air through the first valve, the frame being arranged to be swung laterally to permit adjustment and repair of the atomizer and other parts.

40 10. The combination with a furnace port 70 of a forced draft air duct having an annular outlet port adjacent and coaxial with the same, a cylindrical open ended valve controlling said port, an annular frame coaxial with the cylindrical valve and hingedly 75 mounted for movement about a vertical axis, an oil atomizing device mounted on the frame, and a disk valve slidably mounted on the frame for controlling the flow of atmospheric air through the cylindrical 80 valve.

45 11. In a fuel burner, the combination of forced-draft air inlet means, a hollow valve for controlling said inlet means, a second valve cooperating with the hollow valve for 85 controlling the admission of atmospheric air through the hollow valve to the burner, means for connecting and disconnecting the valves, and means for moving the second valve toward and from the burner to adjust 90 the hollow valve when the valves are connected and to adjust the second valve with respect to the hollow valve when the valves are disconnected.

50 12. In a fuel burner, the combination of 95 spaced front and back ring members defining an annular forced-draft air inlet, a hollow valve member movable within the ring members to control the size of the annular air inlet, a frame hinged with respect to the front ring member, a valve disc supported by the frame, means for moving the valve disc axially of the frame, and means for connecting and disconnecting the valve disc with respect to the hollow valve member.

55 13. In a fuel burner, the combination of 100 spaced front and back rings defining an annular forced-draft air inlet, a tubular valve for controlling the inlet, a frame hinged to the front ring, a tubular member 105 carried by the frame and disposed axially thereof, a disc valve slidable on the tubular member for controlling the admission of atmospheric air through the tubular valve to the burner, means for connecting and disconnecting the tubular and the disc valves, and means for moving the disc valve longitudinally of the tubular member.

60 In testimony whereof I hereunto affix my signature.

WILLIAM S. WILKINSON.
